UNITED STATES PATENT OFFICE.

GEORGE HAYES, OF NEW YORK, N. Y.

VENTILATING-SKYLIGHT.

SPECIFICATION forming part of Letters Patent No. 295,168, dated March 18, 1884.

Application filed July 17, 1883. (No model.)

To all whom it may concern:

Be it known that I, GEORGE HAYES, a citizen of the United States, and a resident of the city, county, and State of New York, have 5 invented certain new and useful Improvements in Ventilating-Skylights, of which the following is a specification.

The object of my invention is to provide for ventilation in skylights by a device which 10 will permit of effective ventilating at or near the ridge of the skylight without obstructing the light, and also to obviate the necessity of elevating the skylight upon the vertical ventilating-walls of a turret, as heretofore frequently done, and which is always an expensive method. The turret arrangement ventilates beneath the bars of the skylight, and does 15 not remove the heated air, which accumulates within the skylight directly under the glass 20 from base to ridge.

Heretofore ventilators consisting of sheet-metal boxes have been placed at the ridge, or so formed in the skylight as to constitute its ridge, for the purpose of removing the heated 25 air at that point; but all such devices occupy space within the light-distributing area, and, being of opaque material, reduce the lighting capacity of the skylight according to their width and length. This defective method is 30 entirely obviated by my herein-described ventilator.

A further object is to obtain cross-draft at the ridge part of the skylight, and so remove heat from beneath the glass; also to diminish 35 weight as far as possible at the ridge, while obtaining greater strength and stiffness in the structure; also more effective ventilation.

The nature of my invention consists in constructing ventilators (one or more) at the highest 40 part of the slope of the skylight and adjacent to the ridge by first creating or providing one or more apertures in the slope, either by cutting out or omitting the glass sufficiently for that purpose in one or more of 45 the sections; and, second, by providing the apertures with glazed hoods, serving to protect the opening or openings from storms and downward currents of air, the glass of the hood or hoods admitting light freely. Each 50 and every hood so constructed is formed with one open face, through which air may pass out or in, and the open face, when desirable, is pro-

vided with one or more stationary or movable louver slats or valves, suitable to regulate the currents of air, and, when desirable, is also 55 provided with a perforated or reticulated screen, serving to keep out snow, hail, or rain in exposed situations.

It also consists in providing the upper edge of the glass at the ventilating-aperture in the 60 slope of the skylight with a cross-bar or border-bar, serving to sustain the upper edge of the glass, said bar being provided with a gutter located beneath the glass, communicating with the gutters of the sloping bars, so that 65 any water reaching the upper edge of the glass beneath the hood at the opening may be readily carried off, and no leakage reach to the interior of the building beneath.

It further consists in extending the ridge- 70 bar lengthwise beyond the slope, when the form of skylight is the hipped variety, to make the extended ridge serve (beyond the apex of the hip) as the ridge to one of the aforesaid ventilator-hoods, and this may be 75 done at both ends of the skylight.

It also consists in combining with the said 80 extended ridge sloping bars running from the extended ridge-bar down to sloping bars of the skylight, whether hip or intermediate bars, to provide for the open face of the hood, and also to constitute a frame, to which, in conjunction with sloping bars and extended ridge-bar, glass may be applied to create the sides and top of the hood, and so form a raised glass 85 roof over the aperture in the sloping section of the skylight.

It further consists in an upward or vertical extension or superaddition to the ridge-bar of the skylight at one or more points intermediate of its length or throughout its entire 90 length, this formation of ridge to serve as a support for one or more plates of glass, constituting a roof to one or more hoods arranged each side of the ridge of the skylight over apertures in one or more of the sections between the sloping bars, so that similar means of ventilation may be provided at such points.

It further consists in combining with the aforesaid vertical-extended ridge sloping bars 100 and vertical bars forming a frame, which, when glazed, will constitute the sides and roof of side hoods of the skylight.

In the accompanying drawings, Figure 1

shows in perspective a skylight of the hipped variety having two of my end or gable ventilators and two of my lengthwise ridge-ventilators, the ventilators having faces open and 5 without valves or louvers. Fig. 2 shows an end elevation of the same, the face of the end or gable ventilator provided with louver-slats. Fig. 3 is a side elevation of one-half the skylight of Fig. 1. Fig. 4 shows a 10 vertical lengthwise section of one-half of the same skylight. Fig. 5 shows in perspective a square skylight (hipped) having four of my gable-ventilators, illustrating how they may be applied to obtain cross-drafts from all 15 sides. Fig. 6 shows in perspective a double-pitch skylight provided with two of my vertical extended-ridge ventilators. Fig. 7 shows in perspective a single-pitch skylight provided with the same ventilator at its highest part or 20 ridge. Fig. 8 is an enlarged cross-section of the border or cross-bar provided with rabbet and gutter, also a curved portion above the glass, to check water and throw it back, if any should reach under the hood so far. The 25 glass is shown in section, and a portion of the side bar is also shown. In Fig. 4 this cross-bar is shown in its proper position in the skylight. Fig. 9 shows in perspective a hipped skylight with end ventilators, illustrating a 30 modification in the hood, which is formed with a glazed portion, as a roof. The face in this instance does not form a gable. By this means the necessity of extending the ridge to the extremity of the hood is avoided, and a wider 35 hood may be obtained. Fig. 10 is a cross-section of the vertically-extended ridge-bar, with portions of the glazing adjacent, also in section. A nosing or metallic water-shed is shown in section at the lower edges of the 40 glass forming the roof of the hood.

A represents the base-frame of the skylight; B, the ridge-bar; C, the hip-bars; D, intermediate bars, and E the glass plates. All of 45 these parts may be constructed in any of the usual forms.

F represents the opening or openings in the slope of the skylight, adjacent to the apex or ridge, the glazing being cut away or omitted at this point in one or more of the sections, so 50 that an outlet-space is left. To protect and shelter this opening from indriving storms, I form a hood or roof of metal frame-work with an open face. I do not confine myself to any peculiarity of form in bending up the metal 55 for the frame-work.

In a hipped skylight to obtain ventilation at the ends, I extend the ridge-bar B, as shown at B', and at its outermost extremity I provide bars G, attached thereto and extending downward at a slope to reach the hip-bars C, as shown, to which their lower ends are attached. I then fill in the triangular space formed by the extended ridge at top, the face-bars G, and the hip-bars C with glass E, which completes the hood, leaving its face open, affording free outlet for air rising from the interior of skylights through aperture F. The upper

edge of the glass section of the skylight is beneath the hood and entirely within under shelter. When a ventilator is formed at each 70 end of the skylight, currents of air may pass in at one end and out at the other, so that a free circulation may be obtained, thereby extracting all the heated air from beneath the glass plates of the skylight, so that they will 75 remain cool at all times.

In situations where exposed to violent storms, snow, hail, &c., I provide the open face of the hood with louver-slats or valves. The slats may be stationary or movable, and 80 as many as necessary. A single-valve sash (glazed) may be used, if desired, so that one or both of the hoods may be entirely closed, if necessary, the sash fitting into the triangular face of the hood; but this would only be 85 necessary in very exposed situations when a very violent storm was raging. Louver-slats are shown in Fig. 2 at I, and, if desired, a screen of perforated metal or wire-gauze may be used to cover the face of the slat-opening 90 and assist in keeping out snow, hail, or rain, while admitting of ventilation. The slats may be of glass or sheet metal, as desired, and of any suitable shape. The upper edge of the 95 sheet of glass at the aperture F, I protect and sustain with a cross-bar or border formed about as shown in Fig. 8, with rabbet a and gutter b of sheet metal. It extends across 100 from one hip-bar to the other, and its gutter communicates with their gutters, so that all water which might possibly reach the upper edge of the glass plate and the cross-bar gutter will be carried off properly, and none reach the interior of the building below.

The two end ventilators in most cases are 105 sufficient to ventilate; but in a square skylight (hipped) four may be used, as in Fig. 5. This gives very effective ventilation; but to obtain more outlets, when desirable, I construct additional ventilators by an upward vertical extension of the ridge-bar or superaddition thereto, as at K, Figs. 1, 2, 3, 4, 7, and 8. I provide 110 apertures in one or more of the glass sections similar to those hereinbefore mentioned, and protect and sustain the edge of the glass with 115 a cross or border bar corresponding with that hereinbefore described, and construct a hood to protect the aperture, as follows: The vertically-extended ridge K is provided with an upper rabbet, as shown in Fig. 10 at c, to support the upper edge of a sheet of glass, L, forming the top or roof of the hood, and to 120 the bar I attach two or more frame-bars, M, sloping from the ridge at any suitable angle to any suitable distance. At the lowermost 125 extremity thereof I secure vertical bars N, their lower ends attached to the sloping bars of the skylight. The glass of the top is marked L, and the sides of the hood are marked O. The sides may be glazed or filled in with 130 sheet metal, as desired. The hood so formed has an open face, which may be supplied with louver slats or valves, as described for the hip-ventilators. By this means a transparent ridge-

ventilator is produced, not in any manner interfering with or obstructing the light, and this form of ventilator may be used without the hip device, if desired, which would of course 5 not be used therewith in any other form of skylight than the hipped variety.

Ventilators for skylights located at the ridge have been made of sheet metal placed upon the structure or so formed in as to constitute 10 its ridge, being in fact an opaque boxing, obstructing the light according to their width and length, and reducing the lighting area of the skylight. My herein-described ventilators permit the light to enter in about the same 15 degree as through the parts of the skylight unoccupied thereby. They do not weaken the ridge, but leave the ridge-bar in its place as the backbone of the structure. Ample ventilating-outlet, securely protected, is obtained, and 20 the removal of heated air at the ridge thoroughly effectuated. The hoods are ornamental, and the greatest degree of lightness consistent with strength may be obtained, while they 25 form transparent or translucent ventilators.

The vertically-extended ridge between the respective rabbets may be perforated to admit 30 passage of air over the main ridge, if desired, and instead of extending the ridge vertically, if already built, to form support for the hood, 35 a plate, perforated or not, may be employed, attached to ridge and hood as a support; or, again, the hood may have a ridge separate supported from the main ridge by standards. These I consider equivalents for the extended 40 ridge hereinbefore described.

What I claim as new, and desire to secure by Letters Patent of the United States, is—

1. In a hipped skylight, the ventilator-aperture F, located adjacent to the ridge, as 45 shown, and provided with a hood or raised roof of metal frame and glass, essentially as shown and described.

2. In a hipped skylight, the combination of extension ridge-bar B' and gable or sloping bars G, with hipped bars C, to form frame for a 45 ventilator-hood, substantially as shown and described.

3. In a hipped skylight, the ventilator consisting of opening F, chamber F', extension-ridge B', sloping or gable bars G, and glass 50 sheets E', in combination with hip-bars C, substantially as shown and described.

4. In combination with gable-bars G, hip-bars C, and glass E, the cross-bar H, provided with rabbet a and gutter b, substantially as 55 shown and described.

5. In combination with ridge-bar B' and gable-bars G, one or more movable or stationary louver slats or valves, I, substantially as 60 shown and described.

6. In a hipped skylight, the combination of two or more ventilators located at but below the apex of the skylight, each constructed as herein set forth, and adapted to operate simultaneously or individually, as and for the purpose described and set forth. 65

7. The vertical extension K or superaddition to the ridge-bar, provided with rabbets c, to form supports for sheets of glass L, essentially as shown and described. 70

8. In combination with super ridge or extension K, the frame-bars M and N, with glass L, and sides O, constituting a hood to an opening, F, substantially as shown and described.

9. In a double-pitch skylight, two apertures, 75 F, provided with a hood, K, having two slopes, each slope glazed, as at L, the glasses supported by frame-work of bent sheet metal resting upon the ridge, and sloping bars of the skylight, substantially as shown and described.
